UNITED STATES PATENT OFFICE.

JOHN C. BEAN, OF LEXINGTON, MASSACHUSETTS, ASSIGNOR TO CHARLES M. MARTIN, OF BOSTON, MASSACHUSETTS.

DESIGN FOR AN ADVERTISING-MEDAL.

SPECIFICATION forming part of Design No. 30,516, dated April 11, 1899.

Application filed February 25, 1899. Serial No. 706,884. Term of patent 7 years.

To all whom it may concern:

Be it known that I, JOHN C. BEAN, of Lexington, in the county of Middlesex and State of Massachusetts, have invented a certain 5 new and original Design for an Advertising-Medal, of which the following is a specification.

This invention relates to a new and original design for advertising-medals; and the essential feature of the design consists in the horseshoe-shaped body inclosing a circular disk within the arms thereof.

Figure 1 represents a face view of an advertising device embodying my design. Fig. 15 2 represents the obverse thereof. Fig. 3 represents a transverse section on the line 3 3 of Fig. 1.

Referring to the drawings, a indicates the body, having the shape of a horseshoe, and b represents a circular disk-shaped portion 20 within the said body close to the inner curve thereof.

What I claim is—

The design for an advertising-medal substantially as shown and described. 25

In testimony whereof I have affixed my signature in presence of two witnesses.

JOHN C. BEAN.
